COUNTING RELAY SIGNALING APPARATUS

Lloyd V. Lewis, Pittsburgh, Pa., assignor to The Union Switch & Signal Company, Swissvale, Pa., a corporation of Pennsylvania

Application November 18, 1944, Serial No. 564,045

10 Claims. (Cl. 177—380)

1 My invention relates to signaling apparatus, and more particularly to a system of relays for counting different numbers of impulses. In its specific embodiment as shown, my invention is employed in control apparatus for yard track indicators for railroads for selectively lighting one of a plurality of numbered signal lamps for informing trainmen on which of a plurality of yard tracks to place their train, and is an improvement upon the apparatus for that purpose disclosed in my Letters Patent of the United States No. 1,972,941, issued September 11, 1934.

A feature of my invention is the provision of an improved relay chain in which the relays are operated one at a time in order in response to a series of impulses, without the use of auxiliary or half step relays or the like as required heretofore, thereby decreasing the number of relays.

Another feature of my invention is the provision of a system of relays of this character which is self checking, characterized by the provision of a temporary holding circuit for the relays so arranged that any counting relay which fails to respond to its assigned impulse is rendered incapable of responding to any succeeding impulse.

A further feature of my invention is the provision of novel means by which a system of relays of the type described is adapted to generate the impulses by which the relays are controlled and in which the impulses generated by one chain of relays operates another similar chain of relays located at a distant point.

I shall describe one form of apparatus embodying my invention and a modification thereof, and shall then point out the novel features thereof in claims.

Referring to the accompanying drawings, Fig. 1 shows one form of signaling system embodying my invention as applied to the control of a yard indicator 1S over a pair of line wires Y and Z, from a central office or tower. The yard indicator 1S may be located adjacent the entrance to a series of yard tracks like the similar device S of my prior patent and includes a series of twenty numbered lamps which are selectively lighted by the operation of a control unit 1CU controlled by a line relay 1LR. To light any one of the indicator lamps, the operator first closes a switch 2G to energize relay 1LR, and then operates a dial switch to interrupt the line circuit a number of times corresponding to the number which he desires to display. The lamp which illuminates the selected number becomes lighted when the interruptions cease and remains lighted until the signal is acknowledged by the trainman

2 by operating a switch 1G, or until switch 2G is operated to open the line circuit. For the information of the central office operator, a miniature indicator 2S may be provided containing indication lamps corresponding to those of the yard indicator 1S and lighted by a similar control unit 2CU governed by a line relay 2LR in series with relay 1LR.

Fig. 2 shows the circuits in detail for the control unit 1CU or 2CU as used in the system of Fig. 1.

Fig. 3 shows a modification of the signaling system of Fig. 1, in which the impulses for selecting the yard indicator lamps are generated by the operation of a transmitter relay T controlled by the office control unit 2CU, under the control of a group of individual keys K1—K10 by which the different lamps are selected. In this form the switches 2G and L and the miniature indicator 2S are not used, the position of the operated key K indicating which lamp is lighted.

Fig. 4 shows the circuits in detail for a control unit similar to that of Fig. 2 but including the circuits for controlling the transmitter relay T by the keys K1—K10, which circuits are substituted for those by which the indicator lamps are controlled in Fig. 2. It will be understood that the control units may be used interchangeably as a transmitter controlled by a group of keys as in Fig. 4, or as a receiver to control a group of lamps as in Fig. 2.

Similar reference characters refer to similar parts in each of the views.

Referring to Fig. 2, it will be seen that the control unit comprises a group of relays controlled by the line relay LR, all of which are normally deenergized. These include two slow release relays LC and LO energized when the line is closed and open respectively, and remain picked up during the periodic operation of relay LR, a chain of counting relays R1—R10 which pick up one at a time in order, thereby registering one to ten interruptions, respectively, of the line circuit, a chain repeat relay CR which is picked up by relay R10 to condition the counting relays R1—R9 to operate through a second cycle to register nine additional interruptions of the line circuit, and a counting relay R20 which operates in place of relay R10 to register the twentieth interruption and is also operated when the line circuit is first closed to render relay R1 responsive to the first of a series of interruptions.

Referring now to Fig. 1, it is to be understood that the device L is an ordinary telephone dial switch except that the number 10 replaces the

zero that ordinarily appears in the last position of the dial, as illustrated in my prior patent, so that any of the numbers 1 to 10 may be selected by a single operation of the dial. The numbers 11-20 are selected by first dialing 10 and then dialing the second digit of the number.

In apparatus of this character it is convenient to light the lamps by alternating current by the connections to terminals BX and CX of the local alternating current supply and to obtain direct current for energizing the relays from a rectifier energized from the same source, as shown in my prior patent. In the present application, to simplify the drawings only the terminals of the direct current source are shown, these being designated by the reference characters B and C, respectively. Furthermore, it is desirable to indicate to the operator when power is available for lighting the lamps of the indicator 1S in the yard, and this is accomplished by obtaining the current for energizing the line circuit from terminals B and C of the source in the yard, as shown in Fig. 1, and by providing a lamp E at the office which becomes lighted when relay 2LR is energized by current from the distant source, in response to the closing of switch 2G.

The mode of operation of the control unit of Fig. 2 will now be described assuming first that the operator closes switch 2G to energize the line relay LR, corresponding to relays 1LR and 2LR of Fig. 1.

When relay LR picks up, it closes a circuit for relay R20 extending from terminal B at front contact *a* of relay 1LR over back contacts *a*, *b* and *h*, respectively, of relays LC, LO and R10, through relay R20 to terminal C. Relay R20 picks up, completing a pick-up circuit at its contact *g* for relay LC, which relay then picks up to establish a stick circuit at its own front contact *a* and to open the pick-up circuit for relay R20, while completing a first stick circuit for that relay which extends from terminal B at contact *c* of relay LC over front contact *b* of relay LR, back contact *c* of relay R1 and the front contact *a* and winding of relay R20 to terminal C. The closing of contact *e* of relay LC of the office control unit causes lamp E to become lighted.

I shall now assume that the operator dials the number two, for example, operating the dial switch L so as to interrupt the line circuit twice.

In response to the first interruption, the energizing circuits for relays LC and R20 are opened by the release of relay LR, but current continues to flow through the windings of these relays to hold them picked up temporarily due to the connection of rectifiers 21 and 22 across their terminals, and the pick-up circuit for relay R1 is closed, which circuit extends from terminal B at back contact *a* of relay LR over front contact *b* of relay LC, back contacts *b* of relays R8 and R9, back contact *c* of relay CR, and front contact *b* of relay R20 through relay R1 to terminal C. Relay R1 picks up, and its contact *c* disconnects rectifier 22 from the winding of relay R20 and closes a second stick circuit for relay R20 which extends from terminal B at contact *c* of relay LC over back contact *b* of relay LR, resistor 23, front contact *c* of relay R1, and the front contact *a* and winding of relay R20 to terminal C. At the same time, relay LO picks up over back contact *a* of relay LR and front contact *b* of relay LC and by opening its back contact *a* prevents the ener-

gization of lamp 1, the circuit for which otherwise would be completed at front contact *d* of relay R1.

When relay LR picks up, following the first line interruption, the energizing circuit for relay LC is closed again, relay LO is held picked up by the flow of current through its winding and rectifier 24, and relay R1 is held picked up over a first stick circuit including its own front contact *a* and back contact *c* of relay R2, which is similar to the first stick circuit for relay R20 already traced. The second stick circuit for relay R20 is opened when relay LR picks up, and relay R20 then releases quickly because this circuit includes the resistor 23 by which the energization of relay R20 has been reduced to a value slightly above its release point, and the circuit furthermore includes no rectifier for retarding its release.

When relay LR releases in response to the second interruption, the energizing circuit for relay LO is closed again, and relay R2 picks up over the circuit from terminal B at back contact *a* of relay LR, front contact *b* of relay LC, back contacts *d* of relays R10 and R20, front contact *b* of relay R1 through relay R2 to terminal C. Contact *c* of relay R2 disconnects relay R1 from rectifier 22 by which it is held energized while relay R2 is picking up, and completes the second stick circuit for relay R1 which includes resistor 23.

When relay LR picks up following the second interruption, relay R1 releases quickly, due to the opening of its second stick circuit, and if there are no further line interruptions, relay LO releases, completing a circuit from terminal BX at its contact *a* over back contact *d* of relay CR and front contact *d* of relay R2 through lamp 2 to terminal CX thereby lighting lamp 2 to display the corresponding number in the yard indicator 1S, and also lighting the corresponding lamp in the miniature indicator 2S at the office.

It will be clear from the foregoing that when relay LR picks up after a number of line interruptions, the last operated counting relay, which registers the number, is held energized over its first stick circuit as long as relay LR remains picked up, but the preceding relay releases quickly, due to the opening of its second stick circuit, leaving only one counting relay energized when relay LR releases, the release of the last operated relay is retarded by rectifier 22 only long enough to effect the energization of the next relay and it consequently releases if the next relay fails to pick up, which prevents the operation of the latter relay in response to any subsequent interruption of the line in case it fails to respond to the one to which it is assigned.

In normal operation, however, a counting relay picks up in response to each release of relay LR and establishes the second stick circuit for the preceding relay to hold it energized. Each relay thereby holds its own pick-up circuit closed, since this circuit includes the front contact *b* of the preceding relay, and at the same time it holds the pick-up circuit for the next succeeding relay open, which circuit includes its own front contact *b* and the back contact *b* of the preceding relay.

Assuming now that the line circuit is opened by the operation of switch 1G or 2G after lamp 2 has been lighted as above described, relays R3 and LO will become energized, the operation of

relay LO extinguishing lamp 2 and relay LC is deenergized and releases and in turn releases relays R2 and R3, and at the office, extinguishes lamp E. The indication displayed by the yard indicator may thus be cancelled, and lamp E extinguished to inform the operator by the opening of switch 1G by the train crew for a suitable time interval, whereupon the operator will open switch 2G to restore the apparatus to normal, if no further operations are required.

Assuming now that switch 2G is closed again and the number ten is dialed, relays R1 to R10 will be operated successively in response to the ten interruptions in the manner described, and when relay R10 picks up it closes a circuit at its front contact g to pick up relay CR, which relay then completes a stick circuit at its contact a extending to terminal B at contact c of relay LC. Relay CR prepares a circuit at its contact d for lamp 10, and at its contact e prepares a circuit rendering relay R1 responsive to the next line interruption so that the relay chain may be operated through a second cycle by dialing the second digit of the numbers 11 to 20. In response to the 20th line interruption, relay R20 picks up in place of relay R10, over front contacts b of relays R9 and CR and back contact h of relay R10.

It will be seen that relay R1 will not respond to the impulse by which relay R20 is energized because its pick-up circuit includes back contact c of relay CR which is now open. It will also be seen that each of the counting relays except relay R10 may be operated twice, but lamp 20 is lighted only in response to the second operation of relay R20 occurring when twenty interruptions have been received.

Referring now to Fig. 4, and more particularly to the transmitter relay T by which the control unit is caused to generate the line interruptions by which it is controlled as above described; in this form of the apparatus a group of ten three-position keys K1—K10 are provided, each of which has a contact a which when moved to the left prepares a circuit for selecting the correspondingly numbered lamp 1 to 10 of Fig. 2, and when moved to the right prepares a circuit for selecting the corresponding lamp in the second group 11—20. Each key K has a second contact b, of which for simplicity but one is shown at the left of the group of keys, by which relay T is maintained in operation to transmit the number of impulses needed to establish a holding circuit for relay T over contact a of the operated key. A starting push button ST may also be used, but for the present it will be assumed that this is cut out of circuit by a connector 25.

I shall assume that the operator desires to light lamp 2, as in the preceding example, and so moves key K2 to the left closing a pick-up circuit for relay T from terminal B at the key contact b over back contacts d of relays LO and LC through relay T to terminal C. Relay T picks up, closing the line circuit of Fig. 3 at its contact b, energizing the line relay LR of the associated control unit and also that of the station control unit, the latter having the lamps of the yard indicator 1S connected to the counting relay contacts d and e in place of the keys, as in Fig. 2.

Relays R20 and LC pick up as described in connection with Fig. 2, and relay LC opens the circuit for relay T which therefore releases to interrupt the line circuit, releasing relay LR, whereupon relays LO and R1 pick up, and since 75

relay R20 is held energized over its second stick circuit by relay R1 as already described, a pick-up circuit for relay T is closed from terminal B at the key contact b over front contacts f of relays R1 and R20. Relay T therefore picks up again reenergizing relay LR, which causes relay R20 to release, and in turn, to release relay T to cause a second interruption of the line circuit.

10. In response to the second interruption, relay LR releases, energizing relay R2, and since relay R1 remains picked up, a new pick-up circuit for relay T is closed, over contacts f of relays R1 and R2, so that relay T picks up to close the line circuit to again energize relay LR. Although relay LR releases relay R1 to open the pick-up circuit for relay T, no further interruptions occur because when relay T becomes energized following the second line interruption it establishes a stick circuit at its contact a, which extends over back contact d of relay CR and front contact d of relay R2 to terminal B at the left-hand contact a of the operated key K2. Relay LO therefore releases, the release of relay LO in the station control unit lighting lamp 2.

It will be clear from the foregoing that since each of the successive interruptions of the line circuit results in the energization of a counting relay over the front contact b of the next preceding relay, the closing of the circuit over the front contacts f of these two counting relays indicates that the operations occurring during the line open period have been completed and thus occurs at the proper time for energizing relay T to terminate the interruption. On the tenth interruption, the operation of an additional relay CR is required, and accordingly a front contact f of relay CR is included in the circuit in series with contacts f of relays R9 and R10 by which that interruption is terminated. It will also be clear that the operations occurring during the intermediate line closed periods are completed when there is only one counting relay picked up, following the release of the preceding relay, and the opening of contact f of the preceding relay occurs at the proper time for initiating the next interruption by releasing relay T, provided the stick circuit including the key contact a and the front contact d or e of the energized counting relay is open.

When the operated key such as the key K2 is restored to its normal position, relay T releases opening the line circuit and restoring the apparatus to its normal condition.

If switch 1G is provided, as shown in Fig. 3, the closing of this switch after it has been opened long enough to release relays LC and LO would complete the first pick-up circuit for relay T, which includes the back contacts d of these relays, so that the apparatus would be set into operation upon the closing of switch 1G to light lamp 2 again, provided contacts a and b of key K2 remain closed. To avoid this, if switch 1G is used, the connector 25 is removed so as to include the contact of the push button ST in the first pick-up circuit for relay T. With this modification the momentary operation of the starting button ST in addition to the operation of a key K is required to initiate the operation of the apparatus, and the operation of switch 1G, which by releasing relay LC opens all of the circuits for relay T except the one controlled by button ST, is sufficient by itself to restore the apparatus to normal.

Although I have herein shown and described

but one form of apparatus embodying my invention and one modification thereof; it is understood that various changes and modifications may be made therein within the scope of the appended claims without departing from the spirit and scope of my invention.

Having thus described my invention, what I claim is:

1. In a signaling system, a two position line relay responsive to a series of impulses, a chain of counting relays, pick-up circuits for a plurality of said relays each including a front contact of the next preceding counting relay, a back contact of the second preceding counting relay of the series and a contact closed by the line relay in one position, a first stick circuit for each such counting relay including its own front contact, a back contact of the next succeeding counting relay and a contact closed by the line relay in its other position, and a second stick circuit for each such counting relay including its own front contact, a front contact of the next succeeding counting relay and a contact closed by the line relay in said one position.

2. In a signaling system, a two position line relay responsive to a series of impulses, a chain of counting relays including one for each impulse, pick-up and stick circuits for a plurality of said relays each including a contact closed by the line relay in one position, the pick-up circuit for each relay including a front contact of the next preceding relay whereby each relay prepares a circuit for the next relay to be operated, said stick circuit for each relay including a front contact of the next relay to be operated whereby each relay when operated holds the circuit prepared by the preceding relay closed until the line relay is operated to its other position, and another stick circuit for each relay including a back contact of the next relay to be operated and a contact closed by the line relay in its other position only.

3. In a signaling system, a two position line relay, a chain of counting relays, pick-up circuits for a plurality of said relays each closed by the line relay in one position each such circuit including a front contact of the last preceding counting relay to be operated and a back contact of the second preceding counting relay of the series, a first stick circuit for each such counting relay closed by the line relay in its other position and including a back contact of the next counting relay to be operated, and a second stick circuit for each such relay closed by the next succeeding relay when such relay is operated by the line relay in said one position and opened by the line relay when it next assumes its other position.

4. In a signaling system, a two position line relay responsive to a series of impulses, a chain of counting relays including one for each of a plurality of said impulses, a pick-up circuit for each such relay including a contact closed by the line relay in one position and also including a front contact of the next preceding counting relay, a first stick circuit for each counting relay closed upon the operation of the line relay to its other position following the energization of such counting relay, a second stick circuit for each counting relay closed upon the next operation of said line relay to said one position only if the next succeeding counting relay becomes energized, and means comprising electronic rectifiers connected to said pick-up and first stick circuits to render each relay slow to release upon the opening of its pick-up or first stick circuit although quick to release when its second stick circuit is opened.

5. In a signaling system, a two position line relay, a slow release relay, a series of counting relays, an initiating circuit for temporarily energizing one counting relay which also serves as the last relay of the series, said circuit including a front contact of the line relay and a back contact of the slow release relay, a pick-up circuit for the slow release relay including front contacts of the line relay and of said one relay, a holding circuit for said one relay including its own front contact and a front contact of the line relay, and an energizing circuit for each counting relay of the series including a back contact of the line relay, that for the first counting relay including a front contact of said one relay and that for each remaining relay of the series including a front contact of the next preceding relay whereby said relays are energized successively, one for each operation of the line relay, said one relay being the last to be energized.

6. In a signaling system, a two position line relay, a chain of counting relays, pick-up and stick circuits for a plurality of said relays each including a contact closed by the line relay in one position, the pick-up circuit for each relay including a front contact of the last preceding relay operated, said stick circuit for each such relay including a front contact of the next relay to be operated, another stick circuit for each such relay including a back contact of the next relay to be operated and a contact of the line relay closed in its other position, a transmitter relay effective when energized to operate the line relay to said other position, and a series of circuits for repeatedly energizing said transmitter relay each of which includes front contacts of the last operated counting relay and of the next preceding relay of the series.

7. In a signaling system, a two position line relay, a chain of counting relays, pick-up and stick circuits for a plurality of said relays each including a contact closed by the line relay in one position, the pick-up circuit for each relay including a front contact of the last preceding relay operated, said stick circuit for each such relay including a front contact of the next relay to be operated, another stick circuit for each such relay including a back contact of the next relay to be operated and a contact of the line relay closed in its other position, a transmitter relay effective when energized to operate the line relay to said other position, a series of circuits for repeatedly energizing said transmitter relay each of which includes front contacts of the last operated counting relay and of the next preceding counting relay, a series of manually operable keys including one for each counting relay, and a series of circuits including a front contact of said transmitter relay for holding it steadily energized, each of which also includes a contact of a different one of said keys and a front contact of the corresponding counting relay.

8. In a signaling system, a two position line relay, a chain of counting relays, a slow release relay, an initiating circuit for energizing one counting relay which includes a back contact of the slow release relay and a front contact of the line relay, a pick-up circuit for the slow release relay including a front contact of said one relay, means for maintaining said slow release relay picked up as long as the line relay is repeatedly energized, pick-up circuits for said counting relays each including a back contact of the line relay and a front contact of the last preceding counting relay to be operated, that for the first

relay of the series including a front contact of said one relay, and those for the remaining relays of the series also including a back contact of the second preceding relay operated, a first stick circuit for each counting relay including a front contact of the line relay and a back contact of the next relay to be operated, and a second stick circuit for each counting relay including a back contact of the line relay and a front contact of the next counting relay to be operated.

9. In a signaling system, a two position line relay, a chain of counting relays, a slow release relay, an initiating circuit for energizing one counting relay which includes a back contact of the slow release relay and a front contact of the line relay, a pick-up circuit for the slow release relay including a front contact of said one relay, means for maintaining said slow release relay picked up as long as the line relay is repeatedly energized, pick-up circuits for said counting relays each including a back contact of the line relay and a front contact of the last preceding counting relay to be operated, that for the first relay of the series including a front contact of said one relay, and those for the remaining relays of the series also including a back contact of the second preceding relay operated, a first stick circuit for each counting relay including a front contact of the line relay and a back contact of the next relay to be operated, a second stick circuit for each counting relay including a back contact of the line relay and a front contact of the next counting relay to be operated, and means for repeatedly energizing said line relay to effect the successive operation of said counting relays, comprising a circuit having a plurality of different branches each including front contacts of the last operated counting relay and of the next preceding counting relay.

10. In a signaling system, a two position line relay, a chain of counting relays, a slow release relay, an initiating circuit for energizing one counting relay which includes a back contact of the slow release relay and a front contact of the line relay, a pick-up circuit for the slow release relay including a front contact of said one relay, means for maintaining said slow release relay picked up as long as the line relay is repeatedly energized, pick-up circuits for said counting relays each including a back contact of the line relay and a front contact of the last preceding counting relay to be operated, that for the first relay of the series including a front contact of said one relay, and those for the remaining relays of the series also including a back contact of the second preceding relay operated, a first stick circuit for each counting relay including a front contact of the line relay and a back contact of the next relay to be operated, a second stick circuit for each counting relay including a back contact of the line relay and a front contact of the next counting relay to be operated, a transmitter relay effective when energized to energize said line relay, a series of manually operable keys one for each counting relay, an energizing circuit for said transmitter relay closed in response to the operation of any one of said keys having a plurality of branches one including a back contact of said slow release relay and the others including front contacts of the last operated counting relay and of the next preceding relay, and a stick circuit for said transmitter relay including its own front contact, a contact of the operated key and a front contact of the corresponding counting relay.

LLOYD V. LEWIS.
